BOILER

Rudolph W. Menk, Joliet, Ill.

Application November 16, 1935, Serial No. 50,190

5 Claims. (Cl. 122—174)

My present invention relates to heating appliances, especially a boiler for heating houses, apartments, and the like with either steam or hot-water.

5 In my co-pending applications for Letters Patent I have disclosed warm-air furnaces wherein sheet-metal plates are employed throughout the structures, said plates being welded together to provide unitary members that are quickly 10 fabricated in manufacture and readily assembled in making an installation. In designing my present boiler furnace I have similarly made use of sheet-metal plates and have made the principal parts of the structure in unitary forms. 15

10 These different parts are of novel design and arrangement, and they provide a finished product of increased efficiency over boiler furnaces at present available. Furthermore, I am able to materially reduce the weight of the structure, and by the special arrangement of the parts 20 which I have provided there is an increased heating area and a longer travel of the products of combustion than in other boiler furnaces so that the water is raised to the required temperature in a comparatively short period of time. 25

Certain objects of my invention reside in providing a boiler that is of novel construction; is economical to manufacture and therefore may be sold at a reasonable retail price to the user; is 30 dependable in performing the functions for which it is designed; is made of sturdy parts to withstand hard usage; and is capable of being readily assembled or erected in a house or other suitable location.

35 Obviously, other objects and advantages of my improved structure will be apparent to persons skilled in the art after the construction and operation thereof is understood from the within disclosure.

40 The foregoing and other objects I prefer to accomplish in substantially the manner herein fully described and as particularly pointed out in the claims hereto appended. The accompanying drawings, to which reference is herein made, 45 form a part of this description, and in said drawings like reference characters identify the same parts where they appear in the different views.

In the drawings:

Figure 1 is a vertical front elevation of my 50 novel boiler furnace.

Figure 2 is a vertical side elevation thereof.

Figure 3 is a vertical section taken on line 3—3 of Figure 1, looking in the direction of the arrows.

55 Figure 4 is a vertical section taken on line

4—4 of Figure 2, looking in the direction of the arrows.

The drawings are more or less schematic and no limitations are to be understood therefrom. However, said drawings disclose a typical or preferred embodiment of my invention such as will enable others to understand the construction and operation thereof by reference to the following description. 5

The boiler is shown surrounded by an exterior housing 10, of relatively light gauge of sheet-metal, that is either rectangular in shape as shown, or may be cylindrical or other shape as desired, or this housing may be omitted without affecting the construction and operation of the boiler. In the event housing 10 is used the front wall thereof is provided with a rectangular panel 11 in which there is an upper fuel feed opening and door 12 and a lower ash-pit opening and door 13. 10 15

It will be understood the structure herein disclosed is adapted for use either for steam or hot-water heating systems, but for the purpose of convenience and to avoid confusion of terms it is designated as a boiler and is shown and described in connection with a hot-water heating plant for residential use. 20 25

The body of the boiler comprises a cylindrical outer wall 14 positioned upright and having a dome-shaped closure 15 for its upper end. This 30 wall and closure, as well as most of the other walls and parts of the structure, are fabricated from sheet-metal plates of a much heavier gauge than that of which the housing is made, and said parts are united by welding to provide tight, 35 leak-proof joints.

The front segment of cylindrical wall 14 is provided with upper and lower openings that align horizontally with the respective feed opening and door 12 and ash-pit opening and door 13. 40

Horizontal and vertical walls connect the corresponding adjacent edges of the feed openings to provide a fuel feed chute 15, and similar walls connect the edges of the ash-pit openings to provide a walled passageway 16 for ready access 45 into the ash pit. Suitable rocker-type grates 17 are disposed horizontally across the interior of the body at about the plane of the top of the ash-pit passageway and thus divide the interior of the structure into a lower ash-pit 18 and an upper combustion chamber 19 as shown in Fig. 3. 50

An inner cylindrical wall 20 of sheet-metal is disposed within and spaced concentrically from the outer cylindrical wall 14 and has an outwardly extended annular flange 21 at its lower 55

end that is welded to the adjacent surface of said outer wall to seal the lower end of the space between said walls and provide an annular chamber or water-leg 22 that encompasses at least the 5 major portion of the combustion chamber 19. Return water is fed into this water-leg from a return pipe 23 that communicates with the lower portion thereof through the body wall 14. The top of this inner wall 20 terminates at about the 10 horizontal plane of the top of the fuel feed chute and is provided with an opening alining with the feed chute to which the edges of said opening are welded.

There is a sheet-metal crown-sheet 24 of 15 dome-shape welded to the top edge of the inner wall 20 to arch over the combustion chamber in the manner shown, and said crown-sheet has an elongated opening that extends from near the front towards the rear and is of a shape to receive 20 a short sheet-metal collar 25 extending vertically above and slightly below the crown-sheet and welded to the edges of the opening. This arrangement provides a horizontally elongated passageway of restricted dimensions for discharge 25 of the hot gases from the combustion chamber into a second or supplementary combustion chamber in the upper portion of the furnace body which has its axis horizontal and intersecting the axis 30 of the main combustion chamber 19. As will be seen, a portion of the water in the structure is above the crown-sheet where its temperature is rapidly raised due to the fact that this body of water surrounds the supplementary combustion chamber and a portion of it contacts the crown-sheet and collar.

Above the crown-sheet there is a large water 35 chamber 26 within the top of the body, which is bounded by the dome 15 and the upper portion of the outer cylindrical wall 14, and into this 40 chamber I insert the supplementary combustion chamber and a novel super-heater in the form of a horizontally disposed elongated structure having circuituous passageways or chambers through which the hot gases and the water pass 45 in intimate relation with each other.

The upper portion of the body wall 14 is provided with relatively large circular openings immediately below the top edge of said wall, said 50 openings being horizontally alined with each other, one opening being in the front of the wall above the fuel chute door 12 and the other opening being in the opposite rearmost segment of the wall 14. A horizontally disposed sheet-metal cylinder 27 is fitted into these openings, as shown 55 in Figure 3, with its ends protruding beyond the wall 14 and provided with front and rear ring-flanges or annular plates 28 and 29 that extend transversely across the ends of the cylinder 27 and are welded thereto to seal the parts. The 60 opening in the front annular plate 28 is closed by a removable head 30 that tightly seals the same against leakage. This cylinder 27 provides a supplementary combustion chamber above and communicating with the main combustion chamber 65 19 through the collar 25.

The lower segment of the supplementary combustion chamber or horizontal cylinder 27 has an elongated opening of suitable shape and size to receive the upper end of collar 25 so that said drum is fitted over the upper end of collar and may, if desired, be welded thereto. This arrangement establishes communication between the combustion chamber 19 and the interior of the drum 27, permitting the hot gases, passing out of 75

the combustion chamber through collar 25, to be discharged into the horizontal cylinder 27.

Since the supplementary combustion chamber is within the upper water chamber 26 and extends transversely through the same, the water in this water chamber is closely adjacent the hot gases circulated in the cylinder 27 so that the latter acts in the manner of a super-heater upon the body of water. 5

Within the supplementary combustion chamber 10 27 a super-heater member is positioned, which member is of drum-like appearance. This super-heater consists of two laterally spaced concentric sheet-metal cylinders 31 and 32 the latter being of smaller diameter than the former and 15 disposed inside and spaced from the same. The cylinder 31 in turn is smaller in diameter than the supplementary combustion chamber cylinder 27 but is of such dimensions that it may readily be inserted into the same through the central 20 opening in the rear annular end plate 29. The forward or front ends of the two cylinders 31 and 32 terminate immediately back of and are spaced a suitable distance to the rear of the head 30 and the adjacent front end of cylinder 27, thus providing a vertical front end passageway 34 for the 25 hot gases.

A removable cap 33 closes the front end of the innermost cylinder 32, while flat annular plates 35 and 36 of ring-like form provide end walls 30 that close the respective front and rear ends of the space between the cylinders 31 and 32, and, as will be seen in Figure 3, the rear end portions of cylinders 31 and 32 protrude beyond the end wall 29 of the upper horizontal combustion chamber 27. 35

Elongated openings extending longitudinally in the upper segments of the super-heater cylinders provide communication between the exterior of the cylinder 31 and the interior of the cylinder 40 32, and the edges of said openings are welded to a sheet-metal collar 37, thus providing a passageway that discharges the gases from the horizontal combustion chamber 27 down into the inner cylinder 22. The area of this passageway is approximately the same as the area of the previously 45 mentioned passageway that is provided by the means of the collar 25 leading upwardly through the crown-sheet into the horizontal combustion chamber 27, and these passageways are preferably disposed in vertical alinement with each other upon the axis of the furnace body. 50

The sheet-metal plates or walls forming the cylinders 27, 31 and 32 are arranged in concentric relation and spaced from each other, and this 55 arrangement, as well as the construction of the walls and the collars 25 and 37, provide means for compelling the hot gases, after leaving the combustion chamber 19, to traverse a circuituous path which leads them up into the supplementary combustion chamber 27 where such gases circulate outside cylinder 31 of the super-heater, after which the said gases pass down through collar 37 60 into the inner cylinder 32 of the super-heater and are discharged at the rear protruding end 65 of said cylinder 32 into the smoke pipe (not shown) leading to the chimney.

The water in the annular water-leg or chamber 21 surrounding the combustion chamber 19 will rise, upon being heated, and pass over the 70 crown-sheet 24 into the vertically disposed cylindrical water chamber 26 in which the supplementary combustion chamber is submerged, and the water passing around the outer cylinder 27 takes up added heat units and is then discharged 75

into the distributor pipe 38 for delivery to the radiators or other heating units in the rooms. However, in order to assist in super-heating the water a certain percentage of the water is bypassed or shunted from the water-leg or annular lower heating chamber 22 to the super-heater by means of a pipe 39 that communicates at its lower end with said water-leg and at its upper end discharges through the lower segment of the cylinder 31 of the super-heater structure. This water, which has been conveyed outside the furnace in transferring it to the super-heater, will circulate in the horizontally elongated super-heating chamber between the sheet-metal cylinders 31 and 32 where it comes directly under the influence of the hot gases that are circulating in the supplementary combustion chamber and also passing out to the chimney through the inside of the cylinder 32, and upon being thus further heated the water passes upwardly out of this chamber through another by-pass or shunt pipe 40 leading to and discharging into the main distributor pipe 38 immediately above the furnace body.

By means of the structure disclosed herein, a main vertical water chamber is provided, which chamber is annular in shape below the crown-sheet to provide the water-leg surrounding the combustion chamber and is cylindrical in shape between the crown-sheet and the dome, and both of these portions are upright on a vertical axis. In the portion of the water-chamber above the crown-sheet there is an auxiliary water chamber which is preferably annular in shape, and it is positioned horizontal with its axis transverse or intersecting the axis of the main water-chamber and the combustion chamber. A portion of the water is conveyed outside the furnace structure in being transferred from the one chamber (water-leg) to the other (auxiliary). The super-heater structure, containing the auxiliary water-chamber, is of unitary form and may be removed bodily from the rear of the cylinder 21, and, being immediately above the combustion chamber, it receives the hottest gases immediately they have started their circuitous path within the furnace to reach the smoke pipe. Thus, all of the water (except that portion which is passing through shunt pipe 39), is in intimate relation with the hot gases at all times. The horizontal cylinders 29, 31 and 32 provide inner and outer horizontal flues for the burning and burned products of combustion, and they are disposed inside the body of water in the upper water chamber 26 and also the two inner cylinders enclose the annular horizontal water chamber which receives its supply of water from the water-leg through the shunt-pipe 39.

As is customary in a structure of this character, the furnace is provided with a safety valve, water-level and pressure gauges, and other accessories it may be deemed desirable to install. Some of these are indicated in the drawings but no specific reference is herein made thereto as such articles form no portion of the present improvements.

It will now be apparent to persons skilled in the art that I have provided a boiler furnace in which there is an absence of the water-tubes or flues usually found in structures of this character and in lieu thereof a heating surface of large area is provided so that the water comes into intimate relation with the ignited and hot products of combustion at all times. In dispensing with these water-tubes or flues the cost of manufac-

ture of the present structure is materially reduced, while it has been found that this furnace possesses the inherent ability to heat the water considerably more speedily than in furnaces provided with water-tubes. Furthermore, the structure is somewhat reduced in size and is lighter in weight which permits more ready handling and installation.

What I claim is:

1. A boiler furnace comprising a substantially cylindrical furnace body embodying a combustion chamber, an annular water-leg surrounding said chamber, a cylindrical water dome above said chamber and forming a continuation of said water-leg, an annular super-heater water compartment within said water dome and having one end protruding outside the furnace, a heating conduit within said super-heater water compartment communicating with the combustion chamber in said furnace body, and a pipe outside the furnace for conveying water to the protruding portion of said super-heater compartment from the body of water in said water leg and cylindrical water dome.

2. A boiler furnace comprising a cylindrical body providing a combustion chamber, a shell surrounding said body and extended above the same to provide a water-dome over said combustion chamber, the lower portion of said shell being spaced radially from said cylindrical body and providing a water-leg surrounding the combustion chamber, an annular super-heater water compartment in said water-dome, a heating conduit extending through super-heater compartment and surrounded thereby, an annular flue surrounding said super-heater water compartment and separating the latter from the water in said water-dome, means for conveying water from the interior of said shell to said super-heater compartment, means establishing communication between the combustion chamber and said annular flue, and means establishing communication between said annular flue and said heating conduit.

3. A boiler furnace comprising a furnace body embodying a combustion chamber, an annular water-leg surrounding said chamber and extending above the latter to provide a water-dome, a cylindrical superheater water-chamber within said dome and disposed with its axis horizontal and intersecting the axis of said water-dome, said water-chamber having an annular shape in cross-section and having an end portion protruding outside said dome, a flue passage-way leading from the combustion chamber around and into said superheater water-chamber and discharging through the protruding end of the latter, and means for conveying water to the protruding portion of said superheater water-chamber from the body of water in said water-leg and water-dome.

4. A boiler furnace comprising a furnace body embodying a combustion chamber, an annular water-leg surrounding said chamber and extending above the latter to provide a water-dome, a cylindrical superheater water-chamber within said dome and disposed with its axis horizontal and intersecting the axis of said water-dome, said water-chamber having an annular shape in cross-section and having an end portion protruding outside said dome, a flue passage-way leading from the combustion chamber around and into said superheater water-chamber and discharging through the protruding end of the latter, and a pipe outside the furnace structure leading from

said water-leg to and discharging into the protruding end portion of said superheater water-chamber.

5. A boiler furnace comprising a furnace body embodying a combustion-chamber, an annular water-leg surrounding said chamber and extending above the latter to provide a water-dome, a distributor-pipe leading from said water-dome, a cylindrical superheater water-chamber within said dome and disposed with its axis horizontal and intersecting the axis of said water-dome, said water-chamber having an annular shape in cross-section and having an end portion protruding

outside said dome, a flue passage-way leading from the combustion-chamber into said dome around, and into said superheater water-chamber and discharging through the protruding end of the latter, a pipe outside the furnace structure leading from said water-leg to and discharging into the protruding portion of said superheater water-chamber, and a pipe leading from the protruding portion of said superheater water-chamber to and discharging into said distributor pipe. 5 10

RUDOLPH W. MENK.
